UNITED STATES PATENT OFFICE.

ROBERT MIDDLETON, OF ELKHART, INDIANA, ASSIGNOR TO ELKHART MUSICAL INSTRUMENT COMPANY, OF ELKHART, INDIANA, A CORPORATION OF INDIANA.

TROMBONE.

1,060,779.

Specification of Letters Patent.

Patented May 6, 1913.

Application filed March 19, 1912. Serial No. 684,849.

To all whom it may concern:

Be it known that I, ROBERT MIDDLETON, a citizen of the United States, residing at Elkhart, in the county of Elkhart and State of Indiana, have invented certain new and useful Improvements in Trombones, of which the following is a specification.

The object of my invention is to locate the tuning device or slide in the slide part 10 of the instrument, and to give the bell a gradual taper from end to end without any break or joint whereby I am enabled to secure correct intonation; and with this and minor objects in view, my invention consists 15 of the parts and combination of parts as will be more fully hereinafter set forth.

In the drawings, Figure 1 is a side elevation of a trombone embodying my invention; Fig. 2 is a top plan view of the same; 20 Fig. 3 is an enlarged detail view of the slide portion of the instrument and the tuning slide; and Fig. 4 is a view similar to Fig. 3 showing the parts moved by the adjusting screw from the position shown in Fig. 3.

25 1 represents the bell of the instrument comprising a single tube from end to end and of gradual taper from end to end. In this connection, attention is called to the fact that there are no tuning facilities or devices 30 in my bell to destroy the perfect taper of the bell, which taper is important for correct intonation in the bell.

2 represents the usual slide of a trombone and 3 the usual hand-hold extending between the legs of the slide.

4 are extensions on the slide 2 over which the tuning slide is constructed to slide. 5 and 6 are the usual tubular extensions connected with the bell and mouth-piece of 40 the instrument, the tube 6 carrying a bayonet joint coupling 7. 7^a is a bridge-piece for said tubes.

8 and 9 are the tubes of the tuning slide connected by the bridging piece 10 and 45 adapted to slide on the extensions 4 of the slide, the tubes 5 and 6 being adapted to slide through the tubes of the tuning slide as will be understood.

11 is a sleeve extending from the bridge-piece 10 between and parallel with the tubes 8 and 9 of the tuning slide, and provided with an interior screw thread of suitable pitch, the lower end of the sleeve 11 being shaped to conform to the perimeter of the 55 hand-hold 3 in order to make a neat joint

therewith while in contact with the hand-hold.

12 is a screw swiveled in the hand-hold 3 in any suitable manner and extending into the sleeve 11 where it intermeshes with the 63 interior thread above referred to, whereby the tuning slide may be moved on the extensions 4 toward or away from the hand-hold so that the instrument may be tuned without increasing the length of the slide 2 65 below the hand-hold 3. One leg of the slide 2 carries the female portion of the bayonet joint 7, whereby it may be locked against movement.

In the conventional trombone, the tuning 70 facilities or devices are all in the bell of the instrument which not only makes it inconvenient to handle but destroys the perfect taper, so important for correct intonation, in the bell. In tuning such conventional instruments, it is necessary to rest it on the 75 floor, perhaps the slides will drop out and possibly become damaged, besides which, the tuning slides in the bell generally stick or buckle, or tilt. The change from high to low 80 pitch is made by substituting the longer tuning slide in the end of the bell for the shorter one and this destroys the perfect taper of the bell, as the sliding part of the bell must necessarily be of straight tubing. By my 85 invention, I mount the tuning slides on the extensions 4 of the slide and adjust them by means of the screw 12 without lengthening the slide beyond the hand-hold 3. Of course, it will be understood that the high 90 and low pitch tuning slides are readily attached to and detached from the extensions 4.

I claim:—

95 In a tuning device for wind musical instruments, the combination with parallel tubes of the instrument and a tuning slide with its ends slidably mounted in said tubes, of a bridge piece on the tuning slide, an elongated sleeve rigidly secured to and extending from said bridge piece parallel with the tubes of the tuning slide and in the direction of the parallel tubes of the instrument, said sleeve being provided with an interior screw thread, a bridge piece extending between the parallel tubes of the instrument having a transverse opening therethrough with a smooth bore, and an elongated screw threaded rod extending through and swiveled at one end in the said 100 105 110

smooth bore opening, the screw threads of the rod being constructed to intermesh with the interior threads of the sleeve, and an enlarged head integral with said rod and 5 positioned on the under side of the second named bridge piece whereby the rod may be revolved to move the tuning slide.

The foregoing specification signed at Elkhart Indiana this 16th day of December, 1911.

ROBERT MIDDLETON.

In presence of—
MYRON W. HARTER,
CHAS. E. SCHROCK.
